UNITED STATES PATENT OFFICE.

OSCAR M. LEICH, OF GENOA, ILLINOIS, ASSIGNOR TO CRACRAFT, LEICH ELECTRIC COMPANY, OF GENOA, ILLINOIS.

ANNUNCIATOR.

1,215,289.

Specification of Letters Patent. Patented Feb. 6, 1917.

Application filed April 16, 1915. Serial No. 21,783.

To all whom it may concern:

Be it known that I, OSCAR M. LEICH, a citizen of the United States, residing at Genoa, in the county of Dekalb and State of Illinois, have invented a certain new and useful Improvement in Annunciators, of which the following is a full, clear, concise, and exact description, reference being had to the accompanying drawings, forming a part of this specification.

My invention relates to annunciators, and more particularly to the annunciators or drop shutters used for telephone switchboards. More particularly, my invention is designed to improve and modify the responsive characteristics of the armature of drops in which the armature has a short shutter arm.

A form of annunciator with a short shutter arm is disclosed in my Patent No. 1,116,598, issued Nov. 10, 1914. I will show my invention herein more particularly as applied to the annunciator set forth in my said patent. This particular annunciator is of the combined drop and jack type although of course the invention is equally applicable to annunciators not combined with jacks.

It is generally understood that the short arm annunciators are more sensitive than the annunciators having the elongated shutter arms, and for this reason it is desirable to maintain the use of the short arm annunciator if possible. It is found that when the long arm annunciators are used that the shutter arms rattle during the time the signal is coming in, thus giving an indication to the operator of the code that is being transmitted over the line. If there is only one series of vibrations, the operator knows that the call is for central, if there are several interrupted series of vibrations, the operator knows that a code is being transmitted over the line, such as one ring, two rings, or the like, and the operator does not plug into the corresponding jack of the calling line, but merely restores the drop shutter, thus saving a lot of time. It has been found that the short arm annunciator does not lend itself to this use as the short arm with its armature is drawn up and remains drawn up at least sufficiently so as not to permit the operator to distinguish any code.

This invention herein is designed thus to adapt short arm annunciators to give this code indication without sacrificing any of the

sensitiveness of this short arm annunciator type.

I will explain my invention more in detail by referring to the accompanying drawing in which—

Figure 1 is a side view partly in section of an annunciator constructed in accordance with my invention;

Fig. 2 is a top view thereof, and

Fig. 3 is an enlarged view similar to Fig. 1.

My improved annunciator may be one of a bank which are supposed to be mounted upon a front plate 1. Rearwardly from this front plate extends side arms 2, 2, which toward the left form a pocket 3 carrying the coil and shell 4. In this specific form herein outlined the coil has a protruding core 5 which projects into a magnetic pole piece 6, which magnetic pole piece is preferably held in a bridge 7 between the arms 2. A jack 75 structure 8 is likewise shown to indicate a combined self-restoring drop and jack structure, the restoring spring being shown at 9. The side plates 2 also carry a spindle or shaft 10 which supports the armature 11. The armature as shown has two ribs 12 punched upwardly out of the metal of the armature proper far enough to leave an open space through which the spindle 10 passes. This armature, similarly to the armature disclosed in my aforesaid patent, is designed to coöperate with the pole piece 6, no adjustment between the armature and pole piece being required when a drop coil is changed as the pole piece and armature are permanently mounted in position. The armature 11 carries the shutter arm 13 of the short type which controls the shutter 14.

Now whenever the electromagnet 4 is actuated, the shutter of course falls. Now in order to cause the armature 11 and arm 13 to rattle or vibrate due to the impulses, I provide a spring 15 bent somewhat in the form of an up-turned J (Fig. 2), which spring is riveted to the armature by the rivet 16. This spring has a rectangular extending leg 17 which projects through a slot 18 cut through the armature 11. The leg 17 of the spring does not normally touch the pole piece 6 as most clearly apparent from Fig. 3. This leg is also arranged of such length that the shutter 14 is released by the shutter arm 13 before the leg 17 of the spring 15 reaches the pole piece 6. Thus the sensitiveness of the annunciator is not reduced.

The spring however pushes the armature away from the pole piece during the interval between each pulsation, and thus causes the rattling characteristic of the long arm annunciators which is of such aid and benefit to the operator in saving useless work.

From what has been thus described it will be seen that without the sacrifice of its sensitive qualities, the additional indicating 10 qualities are provided. As before stated the invention is not limited to the particular form of drop or drop and jack here illustrated, but is applicable in some equivalent manner to other types.

15 Having however thus described one form which my invention may take, what I claim as new and desire to secure by Letters Patent is:

1. A drop annunciator having a drop 20 shutter, an actuating electromagnet, a shutter arm to control said drop shutter, an armature for actuating said shutter arm, said shutter arm being of the short type and extending between said electromagnet and 25 said drop shutter, and a spring interposed between said armature and said electromagnet, said spring being of a substantially U-shape having one extremity fastened to said armature, and having the opposite extremity 30 adapted to engage said electromagnet.

2. A drop annunciator having a drop shutter, an actuating electromagnet, a shutter arm to control said drop shutter, an armature for actuating said shutter arm, said 35 shutter arm being of the short type and extending between said electromagnet and said drop shutter, and a spring interposed between said armature and said electromagnet operative after the release of said drop shutter 40 by said shutter arm to establish a yielding restraint against the attractive force of said electromagnet, said spring being of a substantially U-shape having one extremity fastened to said armature, and having the 45 opposite extremity adapted to engage said electromagnet.

Copies of this patent may be obtained for five cents each, by addressing the "Commissioner of Patents, Washington, D. C."

3. A drop annunciator having a drop shutter, an actuating electromagnet, a shutter arm to control said drop shutter adapted to release said shutter from said shutter arm 50 when said shutter arm is actuated, a gravity restored armature carrying said shutter arm, said shutter arm being of the short type and extending between the rear extremity of said electromagnet and said drop shutter, 55 said shutter arm and armature having a low moment of inertia, yielding means interposed between the said armature and said electromagnet, and positive means for controlling said yielding means whereby said 60 yielding means is inoperative to effectively oppose the movement of said armature until the shutter arm has released the shutter, said yielding means thereafter causing a rattling of said armature when undulatory 65 currents are energizing said electromagnet.

4. A drop annunciator having a drop shutter, an actuating electromagnet, a shutter arm to control said drop shutter adapted to release said shutter from said shutter arm 70 when said shutter arm is actuated, a gravity restored armature carrying said shutter arm, said shutter arm being of the short type and extending between the near extremity of said electromagnet and said 75 drop shutter, said shutter arm and armature having a low moment of inertia, a spring interposed between said armature and said electromagnet, and positive means for controlling said spring whereby said spring is 80 inoperative to effectively oppose the movement of said armature until the shutter arm has released the shutter, said spring thereafter causing a rattling of said armature when undulatory 85 currents are energizing said electromagnet.

In witness whereof, I hereunto subscribe my name this 23rd day of March, A. D. 1915.

OSCAR M. LEICH.
